UNITED STATES PATENT OFFICE.

HUGO HEINRICH, OF ZWICKAU, GERMANY.

ROTARY INCLOSED ENGINE.

1,118,344.

Specification of Letters Patent. Patented Nov. 24, 1914.

Application filed February 25, 1914. Serial No. 820,816.

To all whom it may concern:

Be it known that I, HUGO HEINRICH, a subject of the King of Saxony, and residing at Zwickau, in the Kingdom of Saxony and German Empire, have invented certain new and useful Improvements in or Relating to 5 Rotary Inclosed Engines, of which the following is a specification.

My invention relates to rotary inclosed engines and has for its object to provide a rotary inclosed engine with an internally arranged displacing member such as a blade, piston or the like. This inclosed engine can be used as a prime mover in employing 10 steam, gases or other motive media, or as a blower or a delivery machine for liquids, for compressing gases or for creating a vacuum.

The special characteristics by which the rotary engine built in accordance with my 15 invention is distinguished are as follows: The formation of the inner chamber and outer chamber of a cylindrical drum as working chamber, so that the inner and the outer working chamber can be connected in parallel for the purpose of employing the 20 engine as a twin engine, or in series, in which case the engine can be used, for instance, both as a compressor and a steam engine. As the engine can also be made reversible each chamber can be employed as 25 desired; the axial pressure hitherto arising in engines of this kind is avoided owing to the fact that in a single casing two similar working units or engines are arranged side 30 by side. Consequently the axial pressure arising in one of the engines is balanced by the axial pressure of the other; partitions are employed in the middle cylinder to separate the admission and exhaust ports of the 35 two inclosed engines. Owing to the separation of the admission and exhaust ports of the two engines, this engine is specially suited for separate action, for two-stage action, for example, *i. e.*, for compounding, or 40 the two inclosed engines can be employed for different operations; for example one can be used as a motor and the other as a blower, a pump or the like. The distributing 45 members are arranged in a single casing built hermetically into the wall of the intermediate cylinder of the inclosed engine and this casing can be cut in or out through an opening leading to the exterior; two or 50 more inclosed engines of the same or different sizes are arranged in a casing side by side on a common shaft, so that the engines

can be utilized in different ways. Thus, for example, one can be constructed as a motor and the other as a pump, or both may serve as a motor or a pump, or in the case of simple inclosed engines both may serve as twin or compound engines and in the case of double inclosed engines they may serve as twin-compound or as quadruplex expansion or compression engines; each inclosed engine can be utilized either independently or all may act in conjunction either as prime movers in employing steam, gas or other motive media, or as delivery engines for liquids, for the compression of gases or for creating a vacuum; the two high pressure cylinders and the two low pressure cylinders are connected one with the other by a common intermediate receiver. This intermediate receiver may also advantageously consist of two chambers connected in series which by means of cut-off members can be placed in communication one with the other and can also be connected with the main supply and exhaust conduits for the motive medium in such a manner that the inclosed engine can act either as a compound engine or as a twin engine and, therefore, be converted from a twin to a compound engine, and vice versa. The purpose of the common receiver is to equalize the pressure on the two working sides and thereby to eliminate the axial pressure in all cases with certainty, even in the case in which, owing to accidental injury to the distributing gear or diverse tightness of the packing or joint faces, unequal pressures arise on the two sides.

Various embodiments of the rotary inclosed engine in accordance with my invention are illustrated in the accompanying drawing, in which:

Figure 1 is a cross section, Fig. 2 a longitudinal section, Fig. 3 is a longitudinal section of another modified form of the inclosed engine. Fig. 4 illustrates a constructional form of the inclosed engine in cross-section, in which the middle cylinder is provided with partitions effecting a separation of the admission and exhaust ports and in addition a casing is built in wherein the cut-off members are all arranged. Fig. 5 is a longitudinal section through a portion of the inclosed engine with the casing built into the stationary middle cylinder and inclosing the distributing members. Fig. 6 shows the casing with the distribut-

ing members in elevation. Fig. 7 shows the casing with a modified form of the distributing members in cross-section. Fig. 8 illustrates a constructional form of the inclosed engine in longitudinal section in which two separate inclosed engines are arranged on a common shaft, one of them serving as a motor and the other as a pump. Fig. 9 illustrates a constructional form of the inclosed engine in cross-section in which the two high pressure cylinders and the two low pressure cylinders are connected one with the other by a common intermediate receiver. Fig. 10 is a section of the cut-off members connecting the intermediate receiver chambers, in which the communication between the receiver chambers is cut off, while communication between one of the receiver chambers and the low pressure waste steam pipe and communication between the other receiver chamber and the live steam pipe is established. Fig. 11 illustrates in section a modified construction of the cut-off members connecting the intermediate receiver chambers.

The inclosed engine consists of an inner solid cylinder 1 which is combined axially with an outer hollow cylinder 2 between which a hollow intermediate cylinder 3 is fixed (see Fig. 1). The inner solid cylinder 1 and the outer hollow cylinder 2 rotate respectively within and about the hollow cylinder 3 and remain always in partial contact with this cylinder. A blade 4 is pivoted on the inner cylinder 1 and is displaceably guided in a radial cut in the stationary intermediate cylinder 3. The blade fits snugly against the side walls of the two cylinders 1 and 2, i. e., extends from the cylinder 1 up to the inner periphery of the hollow cylinder 2 concentric with the cylinder 1 and divides the inclosed spaces in such a manner that the motive medium to be supplied (liquids, gases and the like) is separated from the motive medium to be discharged. Consequently, the engine can be employed either as a motor or as a pump. The arrangement of the distributing members adapted to control the admission and exhaust of the motive medium depends upon the particular employment of the engine in view. As this engine embodies the continuous current principle, when it is used as a motor the exhaust members can be dispensed with while when it is employed as a pump, compressor or the like, the admission members are unnecessary.

Live steam enters through the connecting branch 5 provided on the engine casing; it flows through the passage 6 provided in the intermediate cylinder 3, as far as the valve 7 arranged in this cylinder, through which it passes into the working chamber 8 located between the cylinder 3 and the inner solid cylinder 1. By the action of the steam the

inner solid cylinder 1 is driven around with the shaft 9. After one revolution of the engine, i. e. of the rotary element thereof, the live steam comes opposite the inner cylinder 1 by which it is forced through the port 10 into the receiver 11. The steam then passes through the duct 12 which is open to it over the rotary slide valve 13 into the chamber 14 located between the intermediate cylinder 3 and the outer cylinder 2 in which chamber the steam produces a rotary effect and rotating the outer hollow cylinder 2, which like the cylinder 1 is fixed to the shaft 9, after which the steam escapes through the passage 15 and the connecting branch 16 into the atmosphere or into a condenser. When the engine is employed as a pump or a compressor the direction of rotation and the physical action is of course reversed.

The principal advantages obtained with this form of engines are as follows: The blade 4 is doubly utilized in both directions, which is not the case with machines of a similar type as hitherto constructed; the engine can be utilized in various ways for the purpose of obtaining a compound (two-stage) or a twin (duplex single-stage) effect; the passage 6 in the intermediate cylinder 3 can be utilized for heating or cooling purposes according to the purpose for which the engine is to be employed; the inner high pressure chambers are inclosed by the outer low pressure chambers whereby (and this is particularly advantageous in the case of steam engines) radiation of heat is either avoided or greatly reduced. It should also be noted that the rotary members or the rotary cylinders can be formed as a counter weight or provided with a counter weight for compensating purposes. The slides or blades and also the passages or chambers can be multiplied in accordance with requirements without any difficulty.

The inclosed engine illustrated in Fig. 3, which is also constructed as a steam engine, consists of two similar inclosed engines A and B arranged side by side in a common casing 17. By this means the axial pressure produced in one engine is balanced by the axial pressure in the other engine.

In the construction of the inclosed engine illustrated in Fig. 4, the intermediate cylinder 3 is provided with partitions. These partitions 18 and 19 separate the admission and exhaust ports of the two inclosed engines one from the other. By the separation of the admission and exhaust ports of the two inclosed engines, the engines can be used with advantage for separate action, for example for two-stage action, that is to say for compounding, or they may serve different purposes one being employed as a motor and the other as a pump or the like.

In the wall of the intermediate cylinder 3, which is here assumed to be stationary, the valves 20 are also arranged. As shown in Figs. 4 to 7, these valves 20 are mounted in a cylindrical or slightly tapering casing 21, which is preferably made in one piece and inserted and secured in a bore which exactly incloses it, and arranged parallel with the main axis of the intermediate cylinder 3. The passages and ports provided for conducting the motive medium should be adapted for the compounding of the engine as a whole. If the engine is to be used as a twin engine, it is only necessary to bring the delivery passages 22 and 23 together at a suitable place or to omit the partitions 18 and 19. By this arrangement of the distributing members in an interchangeably mounted casing 21, the distributing members as a whole are made easily accessible, as the entire casing 21 is inserted through a bore leading to the exterior (Figs. 5 and 6) and secured by bolts 24 or the like. In order to reach the valves, it is only necessary to loosen the bolts 24, whereupon the valve casing 21 as a whole can be removed from its seat, viz. the bore in the intermediate cylinder 3. All the valves 20 are then exposed and accessible. According to Fig. 7 the valves are replaced by another form of distributing gear (slides) such as could be provided for steam engines or gas engines. Other distributing gear can, however, also be employed.

In the construction illustrated in Fig. 8, two separate inclosed engines are arranged on a common shaft 9 one of them serving as motor and the other as pump. Of these two engines, I is constructed as a steam engine and II as an air compressor. The engines are separately arranged on a common shaft 9 the casings 17 being connected with each other by any suitable means or they may be formed in one piece. The engines may be formed in one piece. The engines may be of the same size or of different size. In the construction as shown the same as in Fig. 3, in each of the casings 17 two similar inclosed engines A and B and A' and B' are arranged side by side, so that the axial pressure arising in one is balanced by the axial pressure of the other. It will of course be understood that each engine may have its own particular construction.

In the modification shown in Figs. 9 to 11 live steam is admitted to the high pressure cylinder in the manner already described but the waste steam is exhausted through the ports 25 for the purpose of balancing the axial pressure on both the operative sides arranged opposite each other.

As shown in Fig. 9, the receiver is divided by a wall 28 into two chambers 26, 27. Communication between these chambers and also with the main supply and discharge con-

duits for the motive medium is established by members of any suitable construction. As shown in Figs. 9 and 10, by way of example, these members may be formed as a double cock 29 and 30 or as a valve as shown in Fig. 12. In the position of the regulating members 29 and 30 illustrated in Fig. 9 the communication of the chambers 26 and 27 is established, and steam can pass into the receivers 26, 27. From the latter, the steam is distributed in the passages 32 and then flows over the distributing members arranged in the casing 21 and through the passages 33 into the low pressure cylinder. Consequently the operation of the steam here corresponds to compounding in case of a two stage expansion. If the cocks 29 and 30 are then set in the position illustrated in Fig. 10, on the one hand communication between the receiver chambers is cut off and on the other hand communication between the chamber 26 and the low pressure steam pipe 34 and communication between the chamber 27 and the live steam pipe 35 is established. The waste steam of the inner cylinder (which has hitherto been the high pressure cylinder) which passes through the passages 31, flows through the cock 29 with the waste steam of the outer cylinder (which hitherto has been the low pressure cylinder) into the common pipe 34; the live steam flows through the common pipe 35 into the inner cylinder and also through the cock 30 into the outer cylinder. The inclosed engine therefore operates as a twin engine. By means of this arrangement great adaptability to the most diverse operative conditions is obtained. The cut-off members such as the cocks 29 and 30 can be coupled in such a manner that when one member is adjusted the other member is simultaneously adjusted.

My improved inclosed engine can be employed not only as a steam engine, but also as a gas engine, compressor, pump or the like. This reversing gear can also be employed for ordinary piston engines.

What I claim is:—

1. A rotary engine including a stationary intermediate cylinder, an inner cylinder eccentrically arranged therein, an abutment carried by said inner cylinder and projecting through the wall of said intermediate cylinder, and an outer cylinder surrounding the said intermediate cylinder and concentrically connected therewith so as to always have a contact with the outer periphery of the said intermediate cylinder, the said abutment being in corresponding contact with the inner periphery of the said outer cylinder.
2. A rotary engine including a stationary intermediate cylinder, an inner cylinder eccentrically arranged therein, an abutment carried by said inner cylinder and project-

ing through the wall of said intermediate cylinder, an outer cylinder surrounding the said intermediate cylinder and concentrically connected therewith, and controlling means arranged in said intermediate cylinder.

3. A rotary engine including a stationary intermediate cylinder having hollow walls for the reception of a cooling or heating medium, an inner cylinder eccentrically arranged in said intermediate cylinder, an abutment carried by said inner cylinder and projecting through the wall of said intermediate cylinder, and an outer cylinder surrounding the said intermediate cylinder and concentrically connected therewith.

4. A rotary engine including a stationary intermediate cylinder having hollow walls for the reception of a cooling or heating medium, an inner cylinder eccentrically arranged in said intermediate cylinder, an abutment carried by said inner cylinder and projecting through the wall of said intermediate cylinder, an outer cylinder surrounding the said intermediate cylinder and concentrically connected therewith and controlling means arranged in said intermediate cylinder.

5. A rotary engine including a stationary intermediate cylinder, an inner cylinder eccentrically arranged therein, an abutment carried by said inner cylinder and projecting through the wall of said intermediate cylinder, and an outer cylinder surrounding the said intermediate cylinder and concentrically connected therewith, and a distributing channel or passage in the said intermediate cylinder.

6. A rotary engine including a stationary intermediate cylinder, an inner cylinder eccentrically arranged therein, an abutment carried by said inner cylinder and projecting through the wall of said intermediate cylinder, and an outer cylinder surrounding the said intermediate cylinder and concentrically connected therewith, and a distributing channel or passage in the said intermediate cylinder.

ing through the wall of said intermediate cylinder, an outer cylinder surrounding the said intermediate cylinder and concentrically connected therewith, and a distributing channel or passage in the cover connected with the said intermediate cylinder.

7. A rotary engine including a stationary intermediate cylinder, an inner cylinder eccentrically arranged therein, an outer cylinder surrounding the said intermediate cylinder and concentrically connected therewith and an abutment forming a partition between the working chambers produced by the said intermediate cylinder and the said inner and outer cylinders.

8. A rotary engine including a stationary intermediate cylinder, an inner cylinder eccentrically arranged therein, an outer cylinder surrounding the said intermediate cylinder and concentrically connected therewith, an abutment forming a partition, and partitions in the said intermediate cylinder to produce separate inlets and outlets in case of two engines being combined as a twin-engine.

9. A rotary engine including a stationary intermediate cylinder, an inner cylinder eccentrically arranged therein, an outer cylinder surrounding the said intermediate cylinder and concentrically connected therewith, an abutment forming a partition, cut-off members and a removable casing carrying said members and adapted to be inserted in an opening in the said intermediate cylinder.

In testimony whereof I have affixed my signature in presence of two witnesses.

HUGO HEINRICH.
